UNITED STATES PATENT OFFICE.

WILLIAM O. VINCENT, OF BRACKETTEVILLE, TEXAS.

HORSE-DETACHER.

SPECIFICATION forming part of Letters Patent No. 665,354, dated January 1, 1901.

Application filed April 13, 1900. Serial No. 12,755. (No model.)

To all whom it may concern:

Be it known that I, WILLIAM O. VINCENT, a citizen of the United States, residing at Bracketteville, in the county of Kinney and State of Texas, have invented a new and useful Horse-Detacher, of which the following is a specification.

This invention relates to horse-detachers, and has for one of its objects to provide an improved device of this character which is to be fitted to the ends of a whiffletree and is designed to disconnect the trace from the whiffletree.

A further object is to provide means for conveniently operating the device from the body of the vehicle so as to release both traces simultaneously and also to support the thills in an elevated position, so as to prevent them being driven into the ground and to enable the driver to guide the vehicle after the horse has been released, and finally to provide a spring-actuated device, so as to insure a positive locking of the trace, the parts of the device being arranged to protect the spring against damage by contact with the releasing lever.

With these and other objects in view the present invention consists in the combination and arrangement of parts, as will be herein-after more fully described, shown in the accompanying drawings, and particularly pointed out in the appended claim, it being understood that changes in the form, proportion, size, and minor details may be made within the scope of the claim without departing from the spirit or sacrificing any of the advantages of the invention.

In the drawings, Figure 1 is a top plan view of a whiffletree provided with the present invention. Fig. 2 is a detail perspective view of a horse-detacher constructed in accordance with the present invention. Fig. 3 is a longitudinal sectional view thereof.

Corresponding parts in the several figures of the drawings are designated by like characters of reference.

Referring particularly to Figs. 2 and 3 of the drawings, 1 designates a ferrule, which is designed to be fitted to one end of a whiffletree and is open at opposite ends. At the outer end of the ferrule there is provided a hollow box-like extension 2, which is offset at

the front side of the ferrule and has its outer end closed by the wall 3, and diametrically opposite, in the rear face of the ferrule, there is provided a longitudinal bifurcation 4, and inwardly from the inner end of this bifurcation is a slot or opening 5, which, in effect, forms a transverse bar or shoulder 6 intermediate of the ends of the bifurcation. Located in a plane at substantially right angles to that of the box 2 and the bifurcation are the opposite outwardly-projecting arms 7, that form a fork which is disposed at the rear side of the ferrule. Pivoted between the opposite ends of the arms of the fork is a rock-bar 8, which is normally disposed in a vertical position, and extending inwardly into the adjacent open end of the ferrule is a transverse pin 9, which is located substantially midway between the opposite arms.

Extending diametrically across the outer end of the ferrule is a lever 10, which has its forward end located within the box 2 and fulcrumed therein upon the pivot-pin 11, so that the outer wall 3 of the box may form a stop to limit the outward movement of the lever. The rear portion of the lever extends outwardly through the bifurcation in the ferrule, and connected to the inner side of its free extremity is a leaf-spring 12, which has its inner free end passed loosely through the opening or slot 5 in the ferrule, so as to be separated from the lever, by means of the transverse bar or shoulder 6. The purpose of this spring is to normally force the outer free end of the lever outwardly, so as to normally receive the free end of the pin 9 within the intermediate opening or perforation 13, whereby the pin is locked.

In the application of the device a ferrule of the hereinbefore-described character is fitted to each end of an ordinary whiffletree 14, as shown in Fig. 1 of the drawings, and a trace 15 is engaged with the adjacent pin 9 by pressing the free end of the lever inwardly to disengage the pin therefrom, whereby the pin may be swung rearwardly or forwardly, as may be desired, to be received within one of the usual openings in the trace, after which the latter is pulled forwardly, so that the free end of the pin may press the lever inwardly until opposite the opening 13 therein, when said lever will automatically snap into en-

gagement with the pin to normally hold it in its locked position. To release the trace, it is merely necessary to force the free end of the lever inwardly, thereby freeing the pin, 5 which will swing forward with the strain upon the trace, and thereby release the latter.

To permit of both devices being operated simultaneously by the driver, who is in the vehicle, the rear end of each lever is provided 10 with a link 16 for connection with the outer end of a strap or other flexible connection 17, which passes inwardly and loosely through a screw-eye 18, that also forms a fastening for the ferrule, and thence to another guide 19. It 15 is preferable to employ a single strap 17, which has its opposite ends connected to the levers of the respective devices, the intermediate portion of the strap being fixedly connected to a ring 20, which is connected to a strap or 20 line 21, that passes into the body of the vehicle and in convenient reach of the driver, so that by pulling upon the line 21 the opposite levers will be operated to simultaneously release the traces. 25

It will be observed that the lever 10 will engage the outer side of the transverse bar or shoulder 6 at its inward limit, so that it is held out of contact with the inner end of the spring in order that the latter will not be subjected to pressure, which would destroy the elasticity thereof, and thus frequently require a new spring. 30

When the strap 21 is operated to release the levers, it will also serve to hold the thills 35 in an elevated position, so as to permit of the vehicle being guided to avoid obstructions

and to prevent the ends of the thills or pole from being driven into the ground.

What is claimed is—

A horse-detacher, comprising a ferrule 40 which is open at opposite ends, and provided with a longitudinal bifurcation in one side and at the outer end thereof, a transverse stop-shoulder located near the rear or inner end of the bifurcation, a lever having one end 45 fulcrumed at one side of the ferrule and opposite the bifurcation, the free portion of said lever working in the outer portion of the bifurcation, the transverse stop-shoulder being in engagement with the lever at its inward 50 limit and supporting the same in the detached position thereof, a leaf-spring having one end connected to the free end of the lever, and its opposite free end working loosely through the inner end of the bifurcation and in rear of the 55 transverse stop, and also out of engagement with the lever, the stop forming means for maintaining the lever separated from the spring, a pair of outwardly-directed arms carried by the ferrule, a rock-bar mounted between the same, and an intermediate transverse pin carried by the bar and normally received within an intermediate perforation in the lever. 60

In testimony that I claim the foregoing as 65 my own I have hereto affixed my signature in the presence of two witnesses.

WILLIAM O. VINCENT.
